UNITED STATES PATENT OFFICE.

JOHN O. WINKS, OF SAN FRANCISCO, CALIFORNIA, ASSIGNOR OF ONE-HALF TO
BRADLEY L. BENSON, OF SAN FRANCISCO, CALIFORNIA.

HAIR CURLER.

Application filed August 24, 1921. Serial No. 494,755.

To all whom it may concern:

Be it known that JOHN O. WINKS, a citizen of the United States of America, residing at 1014 Balboa Building, San Francisco, 5 in the county of San Francisco and State of California, has invented certain new and useful Improvements in Hair Curlers, of which the following is a specification.

The present invention is an improved hair 10 curler and relates particularly to that class of curlers used by women to engage a coil or curl of hair over night, to produce a wavy effect when the curlers are removed and the hair combed out.

15 The objects of the invention include;

1. The provision of a curler for over night use which is small, compact, and which is made entirely of flexible rubber, in order to prevent injury to the hair or discomfort to

20 the wearer.

2. The provision of a non-metallic curler so constructed that the finished article can be sold for a few cents.

25 3. The provision of a hair curler which is inconspicuous when in use and which will have no rigid projections protruding from the head to menace the eyesight or comfort of a bedfellow.

In this specification and the annexed drawings, 30 the invention is illustrated in the form considered to be the best, but it is to be understood that the invention is not limited to such form, because it may be embodied in other forms, and it is also to be understood that in and by the claims following the 35 description it is desired to cover the invention in whatever form it may be embodied.

In the accompanying one sheet of drawings;

40 Fig. 1 is a front elevation of my rubber curler.

Fig. 2 is a side elevation of Fig. 1.

Fig. 3 is a section of Fig. 1 on the line III—III.

45 Fig. 4 is a section of Fig. 1 on the line IV—IV.

Fig. 5 is a view of the reverse side of Fig. 1.

50 Fig. 6 is a side elevation of a fragment of rubber tubing cut in a configuration suitable for making my curler in the preferred form shown in Figs. 1 to 5 inclusive and showing a rubber band positioned thereon for permanent engagement therewith.

55 Fig. 7 is an end view of Fig. 6, and Fig. 8

is a perspective view of a strand of hair coiled helically on my curler and engaged by the rubber band.

Referring to the drawings, Fig. 6, the letter A indicates a section of cylindrical 60 flexible rubber tubing. A portion of the length of the tubing is left intact to form a cylindrical tubular casing, 1, and a portion 2 is cut to substantially semi-circular cross section, to form a tongue adapted to be bent 65 as indicated in dotted lines, in Fig. 6, and inserted within the casing 1 to the position shown in Fig. 4.

I prefer to cut away the wall of the tubing, 70 in substantially circular form, a portion on each side as indicated at 3, to facilitate the bending operation and to better engage a continuous elastic band 4.

When the tongue 2 is inserted in the casing 1 as shown in Fig. 4, it serves a twofold 75 purpose; it reinforces and adds rigidity to the tube 1 and secures the rubber band 4 against withdrawal. The frictional engagement of the tongue 2 against the inner wall of the casing 1 makes it difficult to remove 80 the tongue but still leaves it possible to open to replace the band 4 when it becomes broken or worn.

The apertures 3 serve to give a trim appearance to one end of the curler when made 85 up, and also engage the band 4 in such a manner that no amount of direct pull on the band 4 will withdraw the tongue 2.

The end of the tubular casing 1 remote 90 from the rubber band 4, is bifurcated as indicated at 6 and preferably inclined to facilitate the entrance of the elastic band 4 for engagement as shown in Figs. 5 and 8.

In order to obviate the tendency to split the body portion or casing 1 when the band 95 4 is under tension, I prefer to perforate the wall as shown at 7, Figs. 2 and 4, at the end of the cut 6.

The operation of my curler is as follows:

The device as shown in Fig. 1 is held in 100 one hand and a strand 8 of hair is coiled about the body portion 1 as shown in Fig. 8. The band 4 is then stretched and engaged in the perforation 7 to hold the strand of hair in place until the curler is removed.

I claim:

1. A hair curler comprising a flexible tubular member, a tongue member integral with said tubular member and adapted to be inserted in said tubular member, and an 110

elastic band engaged by said tongue member when so inserted.

2. A hair curler comprising a flexible tubular member, a tongue member integral with said tubular member and adapted to be inserted in said tubular member, an elastic band engaged by said tongue member when

so inserted, and means on said tubular member for removably engaging said elastic band at the end remote from that to which 10 said band is secured.

In testimony whereof I affix my signature.

JOHN O. WINKS.
